DESCRIPTION

U.S. PATENT DOCUMENTS

FIG. 1 is a front perspective view of a monitor television receiver showing our design;

- D. 394,248 * 5/1998 Duan D14/375
D. 411,522 * 6/1999 Chuo et al. D14/375
D. 412,892 * 8/1999 Lee D14/375
D. 413,595 9/1999 Arie D14/126
D. 416,875 * 11/1999 Chuo et al. D14/375

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.
